UNITED STATES PATENT OFFICE

125,569

DESIGN FOR A TOY RATTLE

Frank M. Hoover, Youngstown, Ohio

Application October 5, 1940, Serial No. 95,659

Term of patent 14 years

To all whom it may concern:

Be it known that I, Frank M. Hoover, a citizen of the United States, residing in Youngstown, in the county of Mahoning and State of Ohio, have invented a new, original, and ornamental Design for a Toy Rattle, of which the following is a specification, reference being had to the accompanying drawing, forming part thereof.

Fig. I is a perspective view of a toy rattle, showing my new design; and Fig. II is a view

in diametrical section and to larger scale of one of the disks of the rattle.

The disks comprising the rattle are substantially identical, each having an embossed figure thereon.

I claim:

The ornamental design for a toy rattle, substantially as shown and described.

FRANK M. HOOVER.
